UNITED STATES PATENT OFFICE.

HENRY F. GOLDSMITH, OF PHILADELPHIA, PENNSYLVANIA, ASSIGNOR TO FRIED-BERGER-AARON MANUFACTURING COMPANY, OF PHILADELPHIA, PENNSYLVANIA, A CORPORATION OF PENNSYLVANIA.

DESIGN FOR LACE TRIMMING.

Application filed May 6, 1924. Serial No. 9,494. Term of patent 7 years.

To all whom it may concern:

Be it known that I, HENRY F. GOLDSMITH, a citizen of the United States, residing in Philadelphia, county of Philadelphia, State of Pennsylvania, have invented a new, original, and ornamental Design for Lace Trimming, of which the following is a specification, reference being had to the accompanying drawing, which forms a part thereof.

The design is more particularly adapted for embodiment in trimming for lingerie, although it is applicable to trimming of any kind.

The figure is a plan view of a number of

repeats of a lace trimming embodying my design.

I claim—

The ornamental design for lace trimming, as shown and described.

In testimony of which invention, I have hereunto set my hand, at Philadelphia, Pennsylvania, on this 2nd day of May, 1924.

HENRY F. GOLDSMITH.
